UNITED STATES PATENT OFFICE.

ARTHUR H. STRAMPE, OF PAULLINA, IOWA.

SWITCHING MEANS FOR AERIAL RAILWAYS.

1,242,735.

Specification of Letters Patent.

Patented Oct. 9, 1917.

Application filed March 20, 1917. Serial No. 156,123.

To all whom it may concern:

Be it known that I, ARTHUR H. STRAMPE, a citizen of the United States, and a resident of Paullina, in the county of O'Brien and State of Iowa, have made certain new and useful Improvements in Switching Means for Aerial Railways, of which the following is a specification.

My present invention relates generally to aerial railways, more particularly to the switching means thereof, my object being to provide automatic switching means whereby a car may proceed upon the railway seeking its proper course and automatically acting at the proper switches to maintain such a course.

Generally my invention has to do with overhead carriers such as for instance mail carriers in rural districts, where the railway consists of the main track leading from the postal station to and past switches extending to the various houses along the route, the carriers thus being for instance, electrically driven in which instance the track rails will also be conductor rails. It is to be understood, however, that my invention may be used for the transportation of various means and in various places, as for instance, manufacturing establishments, office buildings and the like, and that the description herein as regards use of the invention in connection with mail distributing systems is by way of example only.

Generally my invention consists in co-operating car and track carried mechanisms automatically acting to permit the car to seek or maintain the line of travel for which it is intended and fitted to carry out at the sending station, and a further object of my invention is to provide automatic switch means which will obviate the necessity of cutting through the main or the switch rail, so that the whole in connected and unbroken relation lend themselves much more readily to effective and efficient supports of minimum number.

In the drawings—

Figure 1 is a side elevation illustrating a portion of the aerial railway embodying my improvements.

Fig. 2 is a plan view thereof.

Fig. 3 is an enlarged side elevation of a portion thereof.

Fig. 4 is a plan view of the parts shown in Fig. 3.

55

Fig. 5 is a detail perspective view of the lifting rails and their operating parts.

Figs. 6 and 7 are respectively a side view and a plan view of the carrier or car illustrated in Figs. 1, 2 and 3, Fig. 6 being partly broken away in section.

Fig. 8 is a vertical cross section through the car taken substantially on the line 8—8 of Fig. 6.

Fig. 9 is a sectional view illustrating a slightly modified form of the invention.

Fig. 10 is a vertical transverse section taken on line 10—10 of Fig. 9, and

Fig. 11 is a detail perspective view of one of the actuating plates of the form of the invention shown in Figs. 9 and 10.

Referring now to these figures, my invention contemplates an aerial railway of which the main rails 10 may be erected in continuous unbroken relation with the inner ends of switch rails 11 secured thereto, so as to enable the erection and support of both the main and switch rails in use in an effective, efficient manner and by the employment of minimum supporting parts, it being obvious that the main and switch rails, the former continuous and the latter rigidly connected thereto mutually contribute to the support of one another and obviate the provision of movable switch points and complicated supporting mechanism necessary in connection therewith.

These as well as other advantages are attained by the particular switching mechanism provided by my invention, which may be mounted either in connection with the main rails 10 adjacent the inner ends of the switch rails 11, or in connection with the switch rails 11 adjacent other switches or off-shoots thereof as indicated at 12 in Fig. 2.

In connecting my improved switching mechanism in place the rails, that is either the main or switch rails, are provided with rigid depending hangers 13 supporting parallel longitudinal beams 14 at their lower ends, between which beams 14 is an intermediate transverse latch rod 15 for a purpose to be presently described.

A pair of upper parallel lifting rails 16 are pivotally connected to the upper ends

of upwardly projecting arms 17, all of which are pivotally connected at their lower ends to the beams 14, said lifting rails being thus shiftable to various elevations dependent upon the particular positions of the supporting arms 17.

Normally the arms 17 are in inclined positions which maintain the lifting rails 16 below the level of the main or switch rails 10 in connection with which they are mounted, and are supported in spaced relation by transverse connecting bars 18, their distance of spacing being substantially less than that of the main or switch rails as clearly seen by reference to Figs. 2 and 4.

Thus, the lifting rails 16 parallel the track rails in connection with which they are mounted, with their forward ends slightly curved as at 19 in Fig. 4 with the curvature of the switch rails, the rear ends of the lifting rails 16 being connected by links 20 to a rocker arm 21, pivotally connected to the beams 14, and in turn connected by a connecting rod 22 to the lower end of a lever 23 intermediately pivoted at 24 to one of the track rails at a point substantially remote from the switching point, the upper free end of lever 23 upstanding above the track rails for engagement by car 30 carried mechanism for this purpose.

From the forward transverse connecting bar 18 of the lifting rails 16 extends a downwardly and rearwardly inclined and pivoted latch bar 25 having a notch in the lower edge thereof at an intermediate point for engagement with the transverse latch rod 15 before mentioned, when the supporting arms 17 are moved to upright positions as seen in full lines in Fig. 3, to 40 elevate the lifting rails 16, the forward ends of which in the elevated positions project above the level of the track rails in connection with which they are mounted.

Connecting the beams 14 is a transverse 45 crank shaft 26 having a crank 27 between said beams and having an end upright arm 28, the latter of which is connected by a connecting rod 29 to the lower end of an intermediately pivoted lever 30 mounted at 50 one side of the switch rails beyond the switching point and for engagement by the same car carried mechanism as previously actuated the switching lever 23, so as to rotate the crank shaft 26 and elevate 55 the lower rear end of the latch bar 25 by engagement of crank 27 therewith, thus disengaging the notch of the latch bar from the transverse rod 15 so as to permit the lifting rails 16 to drop by gravity to their 60 lower inoperative positions, which latter movement is limited by a transverse bar 31 connecting the forward hangers 13 and disposed forwardly of the forward supporting arms 17 for engagement by the latter as seen 65 by the dotted line position in Fig. 3.

As seen in Figs. 3, 4 and 5, the actuating and releasing levers 23 and 30 are at the sides of their respective tracks, but in accordance with the form of the invention shown in Figs. 9 and 10, the corresponding 70 levers, one of which is seen at 23^a, may be intermediately pivoted to cross bars 32 extending between the track rails, for a purpose which will be presently described.

As seen particularly in Figs. 6, 7 and 8, 75 the carrier or car embodying my improvements and which is generally indicated at 33, may have depending sides 34 through which the shafts 35 of the main wheels are mounted, the main wheels being shown at 36 80 spaced apart for engagement with the track rails. In addition thereto, forward and rear pairs of wheels 37 of smaller diameters than the main wheels 36 are journaled at points between the depending sides 34 of 85 the car, these latter wheels being supplemental to the main wheels and spaced apart to conform to the spacing of the lifting rails 16 and for engagement with the latter when they are elevated above the main rails. To 90 this end the supplemental wheels 37 may be of the double flanged type as clearly seen in dotted lines in Fig. 7.

The upper body portion of the car 33 may be closed by any suitable cover 38 utilized to protect mail or other material carried by the car, and which may be locked in use if it is so desired to further safe-guard the contents.

In order to actuate the levers 23 and 30 100 the car 33 has a series of hinged outstanding arms 39 at various elevations above the main wheels and which in their inactive positions are moved parallel to the car side as seen at the right in Fig. 7. When turned 105 to active positions the arms extend outwardly at right angles to the car as seen at the left in Fig. 7, the arm at the desired or proper height being moved to such position when the car starts away from the sending station, to correspond with and actuate the levers 23 and 30 of the particular switch at which the car is to turn off of the main rails, it being understood that the levers 23 and 30 at each switching point are of the 110 same height and a height different from the heights of the levers of the various other switching points.

It will be seen therefore that, it being immaterial which side of the tracks the 120 actuating levers are mounted on, a series of car carried contact arms may be mounted at each side of the car if desired so as to increase the number of switches provided from the main rails, and enable the car to 125 seek and proceed upon the respective switch.

As seen in Fig. 2, there are two switches 11 and it is possible that each switch may have branches 12 on to which it may be desired to again switch the car previously 130

turned from the main rails 10. In this instance the actuating levers are placed between the track rails as seen at 23 in Figs. 9 and 10 and the car is provided at either 5 its forward or its rear end or both, with interchangeable actuating plates 40 having lower stepped edges 41 so as to provide for engagement with other respective actuating levers, the latter of which vary in 10 height as before explained in connection with the levers 23 and 30. It is obvious that by this means the same action may be brought about as previously described in the actuation of the levers 23 and 30, al- 15 though it may be necessary to change the plates 40 of the cars to provide plates having depending steps 41 of greater or less number as seen by comparison of Figs. 10 and 11.

20 Thus it is obvious that when the levers 23 or 23^a are actuated the supporting arms 17 are elevated to more nearly vertical positions and the notch of the latch bar 25 engage with the latch rod 15 to maintain the 25 lifting rails 16 in the inclined elevated position which they assume between the track rails as seen in Fig. 6 so that in the further movement of the car, the supplemental wheels 37 of the latter will right upwardly 30 upon the lifting rails 16, resulting in the elevation of the main wheels 36 clear of the main rails whereby the forward portion of the car will be free for turning movement upon the forward curved end 19 of at least 35 one of the lifting rails so that as the forward supplemental wheels 37 pass beyond the forward ends of the lifting rails 16, the forward main wheels 36 will lower upon the switch rails, this operation being equally 40 true of the rear supplemental wheels 37 and the rear main wheels 36, the car actuating the releasing lever 30 in like manner so as to release the latch bar 25 and permit the lifting rails 16 to lower previous to the passage 45 thereby of the next car.

It is obvious from the foregoing that my invention provides a simple and comparatively inexpensive means for the purposes and to the ends stated, the application of 50 which to an aerial railway of the type described and utilized for various purposes, may be readily and conveniently made, and will provide for a wholly automatic action and at the same time obviate unduly complicated supporting connections for the 55 main as well as the switch rails themselves.

I claim:

1. In a switching mechanism, the combination with main and switch rails, of hangers 60 depending from the main rails, supporting beams connected to the lower ends of said hangers and arranged parallel to the main rails, upwardly extending supporting arms pivotally connected at their lower ends 65 to the said supporting beams, lifting rails

pivotaly connected to the upper ends of said supporting arms and having portions parallel to the main and switch rails, means to limit lowering movement of the said lifting rails, means to hold the lifting rails in 70 their upper operative position, car actuated means for elevating the lifting rails to their upper operative position, and car actuated means adjacent the switch rails for releasing the said holding means. 75

2. In a switching mechanism of the character described, the combination of main and switch rails, a support connected to and depending below the main rails, upwardly inclined supporting arms pivoted in the said support, a pair of lifting rails pivotally connected to the said supporting arms and movable to points above and below the main rails and having portions paralleling the main and switch rails, means for holding 80 the said lifting rails in their upper operative position including a latch member connected thereto and movable therewith, car actuated means adjacent the main rails for moving the said lifting rails to upper operative position, and car actuated means adjacent the switch rails having connections for releasing the said latch member to permit the lifting rails to drop. 90

3. In a switching mechanism of the character described, the combination of main and switch rails, a pair of lifting rails between, and normally below, the main rails and having portions paralleling the main and switch rails, car actuated means adjacent the 95 main rails for elevating the said lifting rails to their upper operative position above the main rails, means to lock the said lifting rails in their upper operative position, and car actuated means adjacent the switch rails for 100 releasing the said locking means to permit the lifting rails to drop.

4. In a switching mechanism of the character described, the combination of rigidly connected and extending main and switch 110 rails, a pair of spaced lifting rails having portions paralleling the main and switch rails and normally between and below the same, means for elevating the said lifting rails above the level of the main and switch 115 rails, means for locking the lifting rails in their upper position, and means for releasing the said locking means to permit the lifting rails to drop.

5. In a switching mechanism, the combination of rigidly connected and extending main and switch rails, a pair of vertically shiftable lifting rails rigidly spaced apart and having portions paralleling the main and switch rails, means for automatically 125 elevating the said lifting rails to upper operative position above the level of the main and switch rails, means for automatically locking the said lifting rails in the upper operative position, and means for automati- 130

- cally releasing the said locking means to permit the lifting rails to drop.
6. In a switching mechanism of the character described, the combination of main and switch rails, vertically shiftable lifting rails having portions paralleling the main and switch rails, and car carried means co-operating with the said lifting rails in their upper operative position.
- 10 7. In a switching mechanism of the character described, the combination of main and switch rails, vertically shiftable lifting rails having portions paralleling the main and switch rails, and car carried means co-operating with the said lifting rails in their upper operative position, said car carried means including wheels independent of the main track wheels thereof and for engagement with the said lifting rails.
- 20 8. In a switching mechanism, the combination with main and switch rails and a car having main wheels movable thereon, of vertically shiftable lifting rails having portions paralleling the main and switch rails, and movable above and below the level thereof, and supplemental wheels carried by the car for engagement with the said lifting rails when the latter are in their upper position.
- 30 9. In a switching mechanism of the character described, the combination with main and switch rails and a car having wheels movable thereon, of means disposed adjacent the intersection of the said main and switch
- rails and co-operating with the car to lift 35 the wheels of the latter from the main rails to the switch rails.
10. In a switching mechanism of the character described, the combination with main and switch rails and a car having wheels 40 movable thereon, of means disposed adjacent the intersection of the said main and switch rails and co-operating with the car to lift the wheels of the latter from the main rails to the switch rails, said means acting to 45 guide the car in its shifting movement.
11. In a switching mechanism of the character described, the combination with main and switch rails and a car having wheels movable thereon, of means disposed adjacent 50 the intersection of the said main and switch rails and co-operating with the car to lift the wheels of the latter from the main rails to the switch rails, and means to automatically shift the first-named means into and 55 out of operative position.
12. In a switching mechanism of the character described, the combination with main and switch rails and a car having wheels movable thereon, of means disposed adjacent 60 the intersection of the said main and switch rails and co-operating with the car to lift the wheels of the latter from the main rails to the switch rails, and car actuated means located adjacent the main and switch rails 65 to respectively shift the first-named means into and out of operative position.

ARTHUR H. STRAMPE.
